(57) **CLAIM**

The ornamental design for an occupancy sensor, as shown and described.

DESCRIPTION

A portion of the disclosure of this patent document contains material which is subject to copyright protection. The copyright owner has no objection to the facsimile reproduction by anyone of the patent disclosure, as it appears in the Patent and Trademark Office patent files or records, but otherwise reserves all copyright rights whatsoever.

FIG. 1 is a perspective view of a first embodiment of a design for an occupancy sensor;

FIG. 2 is a left side elevation view thereof;

FIG. 3 is a front elevation view thereof; and,

FIG. 4 is a top plan view thereof.

The dashed lines in the figures illustrate environment only and form no part of the claimed design. The dotted lines in the figures illustrate the border between claimed subject matter and unclaimed subject matter and form no part of the claimed design.
